Patented Apr. 27, 1920.

INVENTOR
Arthur Salzer

BY Earl P. Shoup

ATTORNEY

UNITED STATES PATENT OFFICE.

ARTHUR SALZER, OF NEW YORK, N. Y.

LAMP.

1,338,194.

Specification of Letters Patent. Patented Apr. 27, 1920.

Application filed May 20, 1918, Serial No. 235,560. Renewed October 24, 1919. Serial No. 333,109.

To all whom it may concern:

Be it known that I, ARTHUR SALZER, a citizen of the United States, and resident of the borough of Manhattan, in the city, 5 county, and State of New York, have invented certain new and useful Improvements in Lamps, of which the following is a specification.

The present invention relates to improvements in lamps, and particularly lamps intended for display or decorative purpose, as distinguished from lamps exclusively for illumination. It is an object of the invention to provide a lamp employing a bulb 10 or globe, of relatively large proportions resembling in appearance an ordinary incandescent lamp of large candle power, in combination with means for attaching the same to a lamp socket. I further propose to provide in such bulb or globe a relatively small lighting element, that is an incandescent lamp of much smaller candle power than would be suggested by the exterior appearance of the device. To this end, I provide 20 in the present embodiment, a plug extension element adapted to support the lighting element at a distance from the light socket, a globe attaching skirt secured to the extension element and exposing the plug thereof, 25 the skirt extending over and obscuring the extension element, and a globe having a neck extending into the skirt, and attached near the plug, so that the exterior appearance 30 of the device is that of a lamp of large power.

In order to add to the display value of the device, the extension element may preferably be of the flashing type, causing the light to intermittently flash. Such a device 40 is shown in U. S. patent to Miller, No. 884,518, dated April 14th, 1908.

A further object is to provide a globe having a large surface suitable for containing decorative designs, advertisements, 45 etc., thus providing a very effective display, of simple and economical construction, and which may be readily attached to an ordinary lamp socket. With the flashing extension element such display will be particularly attractive.

A further object is to provide such a device in which the various parts are independently and conveniently renewable, so that if one becomes out of order, it may be 55 replaced at a relatively small expense.

With these and other objects in view, an

embodiment of my invention is shown in the accompanying drawings, and this embodiment will be hereinafter more fully described with reference thereto, and the invention will be finally pointed out in the claims.

In the drawings;

Figure 1 is a perspective view of one embodiment of my invention;

Fig. 2 is a vertical sectional view thereof, the plug extension and incandescent lamp being shown in elevation.

Fig. 3 is a view in elevation of the plug extension;

Fig. 4 is a vertical sectional view of the skirt; and

Fig. 5 is a view in elevation of the bulb or globe.

Similar reference characters indicate corresponding parts throughout the several figures of the drawings.

Referring to the drawings, the embodiment shown therein comprises a neck member 10 provided at one end with a screw 80 socket 12, at the other end with an external thread 15, and with a plug extension 11 of smaller diameter than the body of said member projecting from the externally threaded end thereof and having a screwthread 85 adapted to engage an ordinary lamp socket.

An incandescent bulb 14 is provided with the ordinary threaded plug 13, which engages the socket 12 of the neck member 10.

A skirt 18 is spaced from and surrounds 90 said neck member. This skirt has an inward top flange 17 and a dependent threaded rim 16 adapted to engage the externally threaded portion 15 of the neck member 10. This skirt is preferably provided near its 95 lower edge with a bead 24 and in its top with a curve 23 for ornamental purposes. The top flange is provided with air holes 25 for the purpose of ventilation.

A globe 19 incloses the incandescent lamp 100 or bulb 14 and is provided with a neck 20 fitting within the skirt 18. This neck 20 is provided, preferably near its upper end, with an annular recess 21, and set screws 22 which pass through holes in the skirt opposite said recess are adjustable for engagement therewith for holding the globe. Any other suitable fastening means may be employed.

The globe 19 is preferably constructed of 110 translucent rather than transparent glass so as to obscure the inner illuminating ele-

ment, and it may, if desired, be provided with colored decorations, printed matter or other display features.

- With my improvements a very effective display is provided, particularly when a flashing plug extension is employed. The globe may be readily removed without disengaging the lamp 14, and all of the parts are readily and independently renewable.
- 10 The device will preferably be sold complete as shown in Fig. 1, and in this form may be immediately attached to an ordinary light socket.

I have illustrated a preferred and satisfactory embodiment of my invention, but it is obvious that changes may be made therein within the spirit and scope thereof, as defined in the appended claim.

I claim:

- 20 An incandescent electric lamp comprising

ing a neck member having a screw threaded socket at one end, an external thread at the other end and a reduced plug extension projecting from the externally threaded end and adapted to engage an ordinary lamp 25 socket, an incandescent bulb adapted to engage said screw threaded socket, a skirt spaced from and surrounding said neck member and provided at its upper end with an inward flange carrying a threaded rim 30 adapted to engage the externally threaded portion of said neck member, a globe inclosing said bulb and provided with a neck 35 adapted to fit said skirt, and fastening means connecting the neck of said globe with said skirt.

In testimony that I claim the foregoing as my invention I have signed my name.

ARTHUR SALZER.
